UNITED STATES PATENT OFFICE.

CLINTON W. TOMS, OF NEW YORK, N. Y., ASSIGNOR TO LIGGETT & MYERS TOBACCO COMPANY, OF NEW YORK, N. Y., A CORPORATION OF NEW JERSEY.

TOBACCO BLEND AND PROCESS OF MAKING SAME.

1,325,060.

Specification of Letters Patent.

Patented Dec. 16, 1919.

No Drawing.

Application filed November 6, 1919. Serial No. 336,046.

To all whom it may concern:

Be it known that I, CLINTON W. TOMS, a citizen of the United States, and resident of New York city, in the county of New York 5 and State of New York, have invented certain new and useful Improvements in Tobacco Blends and Processes of Making Same, of which the following is a specification.

My present invention relates to a new and 10 improved tobacco blend and process of preparing the same.

It is a well known fact that tobaccos grown in different sections, soils and climates differ from one another as to strength, 15 taste, texture, aroma and burning qualities due to the presence therein, in varying quantities, of nicotin, gums, acids, albuminoids, etc. It is also well known by manufacturers of smoking and chewing tobacco products, that very few, if any, of the different 20 types or kinds of tobaccos, in and of themselves, or when taken alone, make an entirely pleasing and satisfying product for chewing or smoking purposes and this is especially 25 true concerning cigarettes. It has long been the practice, therefore, to make up blends by mixing different types or varieties of natural tobaccos and these blends may be varied to quite some extent, but notwithstanding 30 such possible variations, there is, nevertheless, a limitation as to the number of distinctively different and satisfying blends that can be produced, especially for smoking purposes, because as stated all tobaccos have inherent 35 therein, and in varying quantities, certain objectionable acids, gums and nicotin which impart to the tobaccos a disagreeable harshness of taste, and an unpleasantness of flavor and aroma. These render the 40 tobaccos unsatisfactory for smoking purposes, unless they are first treated to eliminate the objectionable matter. There is also a difference in the burning properties of different types of tobaccos, some burn too 45 freely, giving a hot smoke, while others burn too poorly, making it difficult to keep the product lighted unless drawn upon constantly, which is undesirable. It is important and necessary therefore, in making up 50 tobacco blends, to have in mind and provide for all the various peculiarities inherent in the natural leaf.

To be entirely satisfactory, for smoking purposes in general, and for cigarettes in 55 particular, the tobacco blend should have a

pleasing and satisfying taste and aroma, without the harshness or raspiness so often found therein; it should burn freely but slowly, and should produce a substantially white ash. It has been found to be difficult 60 to produce a blend from natural leaves having all these characteristics, and if produced, it is difficult to maintain the same for any considerable period because of the varying nature of the natural leaf from season to 65 season, and also for various other reasons, some of which have to do more or less with the curing processes now generally employed and which it is not necessary to discuss in detail in this specification.

The present invention is based on the discovery by me, after years of experience and study in the cultivation and curing of tobacco, and the preparation of various manufactured products therefrom, that a greater 70 variety of entirely new and distinctive blends, may be produced, faithfully reproduced, and uniformly maintained, by making the blends from a selected group of several different types or kinds of tobacco, some 75 or all of which have been previously treated by impregnation, saturation or otherwise, with an extract taken from a companion tobacco leaf or leaves of the selected group, or from others selected because of their 80 known characteristics, the extract or extracts varying as to strength and quantity employed depending upon the particular 85 blend or characteristic flavor it is desired to produce.

I have also discovered that by treating the selected tobacco leaves with selected tobacco extracts according to my invention that I am able not only to greatly improve the taste, 90 aroma and burning qualities of the products manufactured therefrom, but I am able to entirely eliminate therefrom that unpleasant harshness or raspiness so commonly found in smoking tobacco and particularly in cigarettes. This I consider to be an important feature of my invention,—a desideratum long sought, but never before satisfactorily attained, so far as I am aware.

While I may produce and faithfully maintain, according to my invention, a great 105 variety of distinctive and satisfying blends, from selected groups of practically all, if not all, of the various types, kinds or varieties of tobacco grown, I will, for the purposes of this specification, give only one ex- 110

ample of a new blend, simply by way of illustration in order that the invention may be fully understood and practised by those skilled in the art, but I wish it understood 5 that such example is only by way of illustration and is not to be taken as in any way restrictive, except as I may be restricted by the terms of the appended claims, since it will be perfectly obvious to any one skilled 10 in that art, after reading this disclosure, that variations in the kinds or types of tobacco employed; of the applied extracts, their strength and quantity as well as the method of treatment, may be made within 15 wide limits without departing from the true spirit and scope of the invention.

Modified tobacco.

In preparing to make a new and distinctive blend according to my improved process, I proceed as follows:

Having first determined the general nature of the blend, I then carefully select the different types or kinds of tobacco best suited for such a blend. If the blend is to be of say medium strength, I would select the following tobaccos; in about the proportions stated, Virginia 40 parts, Burley 25 40 parts, Green River 5 parts, and Wisconsin cigar leaf, 15 parts, with or without a small proportion of Turkish tobacco, depending upon whether or not a Turkish flavor is desired. I mention the four domestic tobaccos referred to and the stated proportions, merely by way of specific illustration 30 and it will be obvious that I may select another group, or substitute another or other tobaccos for some of those mentioned, and I may also add others to the three mentioned.

Having selected a particular group of tobaccos and always keeping in mind the peculiar characteristics of the blend it is sought to produce, I then prepare my tobacco extract or extracts to be applied to the selected 40 leaves, it being understood that such extract or extracts may be applied to all, or a portion only, of each kind or type of tobacco selected. I have found that the best 50 results are obtained by applying to a mild or light tobacco an extract of a somewhat stronger and heavier tobacco. For example, I have obtained very satisfactory results by applying an extract of burley to Virginia 55 tobacco, and an extract of Green River, or a heavier and stronger tobacco, such as Wisconsin or Porto Rican cigar leaf, to Burley and so on. In every case I use the same care in selecting the extracts as I do in 60 selecting the tobaccos in the first instance, always having in mind the peculiar characteristics of the tobaccos from which the extracts are procured, as well as the characteristics of the tobaccos to which the extracts 65 are to be applied, and I prefer to ap-

ply the extract of one kind or type of tobacco to another or others having somewhat similar characteristics but preferably of a milder nature than the tobacco from which the extract was taken.

I have already explained that a great deal of the unpleasant harshness or raspiness experienced when smoking certain kinds of tobaccos, is due to a very large extent, to the various juices, acids, nicotin, albuminoids, and gums existing in varying quantities and character in each type or kind of tobacco. I have found that these can be substantially eliminated or materially reduced in strength and quantity by treating the leaves from which the extracts are made, or by treating the extracts themselves, with a small quantity of hydrochloric or an equivalent acid. I prefer, therefore, to so treat the leaves from which the extracts are to be made or treat the extracts themselves, before applying the same to the tobacco leaves according to my method. The reduction of the nicotin percentage as well as the other elements above recited, not only aids in removing the harshness as stated, but also seems to generally improve the tobacco treated with such modified extracts, and this is another feature of the invention.

Having thus decided upon the extracts to be used and the particular strengths, (which of course may vary to suit the conditions) I proceed to apply the same separately to the selected tobaccos in their natural state after they have been cured in the usual way. The application may be made in any convenient way, as by saturation, impregnation, spraying or otherwise. I may apply a 10 per cent. solution of each extract, or the strength of the different extracts may vary 105 in any particular blend. All of this is predetermined and noted according to the result desired, and having once produced the blend it is a simple matter to faithfully reproduce and maintain the same blend 110 standard, which is a matter of very great importance in a product of this kind, the reputation of which is soon lost if the standard of quality falls.

I may obtain the extracts in any of the well known ways from the leaves themselves or from the stems, shorts or so-called "scrap", but in every case each extract should be made separately from selected stock and then properly labeled so that no error will 120 be made in its application to the particular type or kind of tobacco to be treated.

In treating the leaves with the extract it is not my purpose or intention to entirely destroy the characteristics of the natural leaf so treated, but to simply add to or "modify" such characteristics. For instance, I do not propose to convert a Virginia into a Burley leaf, nor a Burley into a Wisconsin or a Porto Rican or some other leaf. 130

The result of the treatment according to my process is the creation of what may be termed a distinctly new or "modified" tobacco, as I add an additional, but selected 5 tobacco essence or extract having known characteristics, to cured tobacco of good quality and without first removing therefrom any of its natural or inherent characteristics. By this procedure the treated 10 leaves are given a more distinct tobacco flavor because they contain a greater percentage of tobacco essence.

Of course I do not wish to be understood as limiting myself to the particular types or 15 kinds of tobaccos herein mentioned, nor to any specific number of types or kinds in a particular blend, but in every blend I contemplate employing at least two or more types or kinds, some or all of at least one 20 of which is treated with a particular extract or extracts depending upon the result desired.

Since those skilled in the art may readily ascertain the peculiar characteristics of the 25 different kinds or types of tobacco as well as the extracts made therefrom, the making and maintaining of any particular blend, according to my improved process or method, becomes very simple, and obviously 30 by varying the strength of the extracts employed as well as the application thereof to the different types or kinds of tobacco, a great variety of distinctively new and pleasing blends may be produced, faithfully 35 reproduced and maintained, notwithstanding the variations in the natural leaf.

After the leaves have been selected and treated as described they are blended in proper proportions according to the result 40 desired. If a strong and heavy flavor is desired a greater proportion of Green River or other types of the heavier kinds of tobacco are employed. If a light or mild flavor is desired then a preponderance of 45 Virginia or other light leaf will be employed.

After the treated tobaccos have been properly blended in the manner stated, the whole mass may be submerged in a casing solution 50 consisting principally of licorice, alcohol, glycerin and sugar. The mass is then subjected to heat treatment in a suitable tobacco drier or conditioning apparatus, the temperature therein ranging from 200° to 55 240° F. This treatment is continued for about six hours or more, and serves to permanently "fix or set" the applied casing as well as the applied extracts and improves the burning quality of the tobacco.

60 After the heat treatment the tobacco is subjected to a bath of cool, moist air in a humidifying system. This also affects the burning properties of the tobacco and serves to give a cooler smoke.

65 The whole mass of tobacco thus treated

is then subjected to pressure in a suitable press sufficient to cause a thorough distribution of the added extracts, casing solution, etc., throughout the mass, but not so great a pressure as to expel such substances from 70 the mass. This pressure is maintained for approximately two hours during which time the mass undergoes a certain setting and curing action due to its previous treatment whereby the juices, extracts, etc., are uniformly distributed and the flavor materially improved. 75

The tobacco is then ready to be manufactured into the desired product. If it is to be prepared for a cigarette filler it is cut into 80 thin shreds and subjected to a temperature of about 140° F., and these are then softened by the application of glycerin and alcohol.

In some cases, as where a more distinctive flavor is desired, I may sprinkle over the tobacco leaves during any stage of the described process, a relatively small percentage of powdered coffee or an extract thereof 85 in powdered form. I have discovered that powdered coffee or an extract thereof 90 in powdered form combines with tobacco in a peculiar way and produces a remarkable change in its flavor and aroma. This however, is a modification of the main idea of my invention and may be availed of or not 95 depending upon the character of blend desired.

I am aware that it has been proposed to treat certain domestic tobaccos of low grade and poor quality from which the nicotin, 100 gums and juices have been extracted, with an extract of Habana or Cuban tobacco in order to give them the flavor of Habana or Cuban tobacco; but such treatment is not to be confused with my new "modified" tobacco 105 blend and method of producing the same. The two products and processes are distinctly different, since in the former case, the object sought is simply to render usable an otherwise low grade and practically useless tobacco; while the objects sought by me are to create entirely new or "modified" 110 tobaccos from which a great variety of distinctive blends may be produced, reproduced and faithfully maintained, and wherein the 115 taste, aroma and burning qualities of the better grades of tobacco are improved.

What I claim and desire to secure by Letters Patent is:—

1. As a new product of manufacture, a 120 tobacco blend comprising a mixture of selected tobaccos of different kinds or types, at least one of which has been treated with a tobacco extract having characteristics as to strength of flavor different from the tobacco to which it is applied. 125

2. As a new product of manufacture, a tobacco blend comprising a mixture of selected tobaccos each having different characteristics as to flavor, taste and aroma, cer- 130

tain of the tobaccos of the group having incorporated therein extracts obtained from tobaccos different from those to which the extracts have been applied.

5. 3. As a new product of manufacture, a tobacco blend comprising a mixture of selected tobaccos of different kind or quality, at least one of which has been treated with an extract of a stronger flavored tobacco.

10 4. As a new product of manufacture, a tobacco blend comprising a mixture of different kinds of tobacco, at least one of which has been treated with an extract of a tobacco having different characteristics 15 from the one treated, whereby the blended mixture is given a distinctive flavor.

5. As a new product of manufacture a tobacco blend comprising a mixture of different kinds of tobacco, at least one of 20 which has been treated with an extract of a tobacco having different characteristics from the one so treated, and powdered coffee incorporated in the mixture.

6. The method herein described of making 25 a tobacco blend, which consists in selecting definite proportions of a plurality of different kinds or types of tobaccos having known characteristics as to taste and aroma, and treating at least one of such with a 30 tobacco extract different from the tobacco treated, and then mixing the tobaccos.

7. The method herein described of making 35 a tobacco blend, which consists in selecting

definite proportions of a plurality of different kinds or types of tobacco, treating 35 some of the several kinds so selected each with a different tobacco extract, then mixing the tobaccos so treated and subjecting the mixture to a temperature of approximately 200° F. to "fix or set" the applied 40 extracts.

8. The method herein described of making 45 a tobacco blend, which consists in selecting definite proportions of a plurality of different kinds or types of tobacco having known characteristics as to taste, aroma and 50 burning quality, then treating some of the several kinds of tobaccos so selected, each with a contrasting tobacco extract, then mixing the tobaccos so treated and subjecting the mixture to a bath of cool, moist air.

9. The method herein described of making 55 a tobacco blend, which consists in selecting definite proportions of a plurality of different kinds or types of tobacco having known characteristics as to taste, aroma and 60 burning quality, then treating some of the several kinds of tobaccos so selected each with a different tobacco extract, then mixing the tobaccos so treated and subjecting the mixture to a bath of cool, moist air, and finally to prolonged heavy pressure.

Signed at New York city, in the county of New York and State of New York, this 5th day of November, A. D. 1919.

CLINTON W. TOMS.
